Primary Examiner — Ania Aman(74) *Attorney, Agent, or Firm* — Lewis Kohn & Walker LLP; Kent M. Walker; Kari Moyer-Henry(57) **CLAIM**

The ornamental design for a concrete fire bowl, as shown and described.

DESCRIPTION

FIG. 1 is a top perspective view of the concrete fire bowl embodied in the present invention;

FIG. 2 is a bottom perspective view of the concrete fire bowl from FIG. 1;

FIG. 3 is a top view of the concrete fire bowl from FIG. 1; FIG. 4 is a bottom view of the concrete fire bowl from FIG. 1;

FIG. 5 is a side view of the concrete fire bowl from FIG. 1; FIG. 6 is an end view of the concrete fire bowl of FIG. 1; and,

FIG. 7 is a side perspective view of the concrete fire bowl of FIG. 1.

The broken lines shown in FIGS. 1, 2, 3 and 4 are included for the purpose of illustrating portions of the article that form no part of the claimed design. The broken lines shown in FIG. 7 are included for the purpose of illustrating environmental context and forms no part of the claimed design.
